ATTORNEY

UNITED STATES PATENT OFFICE.

FREDERIC BARR, OF NEW YORK, N. Y.; THE EQUITABLE TRUST COMPANY OF NEW YORK, OF NEW YORK, N. Y., A CORPORATION OF NEW YORK, EXECUTOR OF SAID FREDERIC BARR, DECEASED.

ELECTRIC PULL-SOCKET.

1,230,983.

Specification of Letters Patent. Patented June 26, 1917.

Application filed October 31, 1911. Serial No. 657,780.

To all whom it may concern:

Be it known that I, FREDERIC BARR, a citizen of the United States, and resident of New York, in the county of Kings and State of New York, have invented certain new and useful Improvements in Electric Pull-Sockets, of which the following is a specification.

My invention relates particularly to the construction by means of which the parts of a switch are supported in the casing and the operating chain or cord is guided.

The parts of a pull switch are customarily supported by a porcelain member contained in a metallic shell and a chain by means of which the switch is operated is guided at the point where it passes through the shell by means of a metallic eyelet or bell fastened either to the shell or detachably secured to the porcelain. In this construction difficulty has been encountered in properly positioning the parts and insulating the chain so as to prevent the operator from being shocked.

It is my object to simplify the construction and facilitate the assembling of the parts and also their separation and also to completely insulate the operating chain from the shell.

Briefly considered, the invention contemplates the use of a porcelain chain guide or bell. In its preferred form this porcelain bell is integral with the porcelain block which supports the switch parts. Preferably the switch block is formed in two parts and one-half of the chain guide is carried by each of the parts. The two parts of the porcelain block are suitably secured together and inclosed in a two part socket shell, the chain guide or bell projecting therefrom.

Fig. 1, is a side view of a lamp socket pull switch embodying my invention, the shell being shown in section.

Fig. 2, is an outside view of the entire construction of Fig. 1.

Fig. 3, is a plan view of the construction of Fig. 1, the cap of the shell being removed and showing the upper part of the porcelain body or block.

Fig. 4, is a plan view of the lower part of the porcelain block of Fig. 1.

Fig. 5, is a side view of the parts of the porcelain and switch members, the upper

part of the porcelain being shown separated from the lower part.

Fig. 6, is a side view and partial section of a pendant switch embodying a modified form of my invention.

Fig. 7, is a fragmentary detail sectional view of another modification.

In the construction illustrated in Figs. 1 to 5 inclusive, the block which carries the switch mechanism is formed in two parts 1 and 2 of porcelain or other suitable insulating material. For convenience, as is customary, these members will be termed "porcelain" 1 being the upper porcelain and 2 the lower porcelain. The two parts 1 and 2 are suitably secured together as for instance, by means of one or more screws such as 3, 3. In this particular construction the stationary switch contacts (not shown) are carried by the lower porcelain 2 which also carries the center lamp contact 4 and the screw socket 5 for the lamp. A stationary spindle 6 is suitably carried by the lower porcelain 2 and affords an axis of rotation for the rotatable switch member 7 shown dotted in Fig. 5. A switch member 7 is carried by a porcelain or other insulating disk 8 which is adapted to be rotated step by step by means of an oscillating operating ratchet lever 9 which is mounted on the spindle 6. A helical spring 10 mounted on the spindle 6 has one end engaging the adjustable abutment 11 and the other end engaging the oscillating lever 9. The switch is operated manually or otherwise by means of a flexible chain or cord 12 (which is commonly termed a chain) which has its inner end secured in a suitable manner to the oscillating lever 9. Insulating material such as fiber as is customarily employed in lamp and switch sockets, may be used as at 14, 15 and 16 as desired. The parts are inclosed in a shell usually of metal consisting of a body member 17 and a cap 18 suitably secured thereto for instance by means of any type of fastening device or catch as indicated at 19, 19, the cap fitting over the upper edge of the body.

The porcelain chain guide in the form shown in Figs. 1 to 5 inclusive is formed of two parts 20 and 21 integrally formed as parts of the upper and lower porcelains 1 and 2 respectively, the two parts constituting when together a guide through which

the chain readily passes. Inside the socket the chain is guided in a semi-annular recess bounded by the horizontal flanges of the upper and lower porcelain parts 1 and 2, the periphery of the insulating disk 8, the vertical walls 22 and 23 of the upper porcelain, and the inner surface of the fiber insulation. At the point where the chain passes through the shell it is insulated absolutely from the shell by means of the porcelain guide. As it is of course possible to use other well known materials possessing the necessary insulating and structural qualities for the integral switch base and chain guide, it will be understood that the term "porcelain" is used herein in a generic sense.

To facilitate the assembling of the parts in the shell, the lower part or body of the shell 17 is formed with an open slot 25 as shown by dotted lines in Fig. 2. It will thus be seen that when the cap 18 is detached from the body of the shell the porcelain and switch mechanism may be readily removed by simply lifting it from the shell body 17 or considered conversely, if the cap be fixed, the body of the shell may be detached from the cap and from the porcelain and switch mechanism.

The terminals 26 and 27 for the circuit wires are preferably located in recesses in the upper porcelain 1 as indicated in Figs. 3 and 5. The upper porcelain 1 is provided with a shoulder or projection 28 which fills in the upper end of the slot 25 of the body 17 of the shell and thus assists in preserving the parts in their proper relative positions. The upper end of the porcelain 1 may be closed in by a boss as shown at 29 in Fig. 5 so as to completely insulate the upper end of the spindle 6 from the circuit wires (not shown) and the terminals 26 and 27.

In the construction shown in Fig. 7 the two parts 30 and 31 of the chain guide bell are integral with the parts 1 and 2 of the porcelain body and a thimble or sleeve 32 is provided which surrounds the parts 30 and 31 and has a flange 33 inside of the edges of the shell members 17 and 18. This may be employed when it is desired to reinforce the porcelain bell or to conceal the porcelain if for any reason that should be desired.

In the construction shown in Fig. 6 the switch mechanism is carried by a single piece of porcelain 40 inclosed in a shell formed of two parts 41 and 42. This construction is designed particularly for what is termed a pendant switch. A porcelain guide member 43 is provided in the lower part of the body 41 of the shell having a passage 44 for the chain 45. This guide 43 may be made separate from the porcelain 40 or constructed integrally with it if desired. In the form shown, the lower part 65 of the porcelain 40 is provided with a guide

slot or passage 46 for the chain. In this construction it will be noted that the chain is also completely insulated from the metallic shell and the parts are conveniently related for assembling or separation. This form is specifically claimed in my Patent #1,107,246. 70

It will be obvious that many changes may be made in details of construction and arrangement of the parts without departing from the spirit or scope of my invention except so far as the claims may be limited to details which I consider of particular importance. 75

What I claim is:—

1. In a pull socket switch, a porcelain body having a porcelain guide or bell integral therewith and projecting laterally therefrom and a metallic shell surrounding and inclosing the porcelain body from which the porcelain chain guide or bell projects. 80 85

2. In a pull socket switch, a two part porcelain body having switch mechanism and a two part porcelain chain guide having its parts integrally connected respectively with the two parts of said porcelain body. 90

3. In an electric socket construction, a block of insulating material having a recess in the outer end and a recess in the side connecting with the end recess, a circuit terminal having a base portion in said end recess and a flanged lug portion extending at substantially right angles into said side recess, a screw passing through said base portion and into said insulating block and securing said circuit terminal to said block, a binding screw screwed into said flanged lug portion in said side recess and substantially at right angles to said securing screw and a shell inclosing said parts. 105

4. In a device of the character described, in combination, a casing for inclosing a pull chain operated switch mechanism, a base for supporting such switch mechanism and provided with an integral portion extending through said casing, said portion constituting a guide for the pull chain of such switch mechanism. 110

5. In a device of the character described, in combination, a casing having an opening, and a divided insulating switch base therein having a projection extending through said opening, the line of division of said base passing through said projection and the adjacent faces of the latter being provided with complementary grooves constituting a passageway for the operating member of the switch. 115 120

6. In a device of the character described, a casing having a lateral opening, and a transversely divided insulating base inclosed in said casing and provided with a radially projecting bushing extending through said opening, the line of division of said base 125 130

passing also through said bushing, said base having an interior recess for a switch mechanism and said bushing having a passageway communicating with said recess and constituting a guide for the switch operating member.

7. In a device of the character described, a base for supporting a pull chain operated switch mechanism and having an integral projecting portion adapted to extend

through a suitable casing, said projecting portion having an opening therethrough for the pull chain of the switch mechanism and said opening being flared at its outer end.

FREDERIC BARR.
